UNITED STATES PATENT OFFICE.

EDMUND B. POWERS, OF NEW YORK, N. Y., ASSIGNOR TO EMPIRE RAILWAY APPLI-
ANCE CORPORATION, OF NEW YORK, N. Y., A CORPORATION OF NEW YORK.

ANTICREEPING DEVICE FOR RAILWAY-RAILS.

1,118,308.

Specification of Letters Patent. Patented Nov. 24, 1914

Application filed February 8, 1913. Serial No. 747,025.

To all whom it may concern:

Be it known that I, EDMUND B. POWERS, a citizen of the United States, residing in the city of New York, borough of Brooklyn, in the county of Kings and State of New York, have invented a certain new and useful Improvement in Anticreeping Devices for Railway-Rails, of which the following is a specification.

10 The invention relates to that class of anti-creepers in which the rail is held by a roller engaged between the base-flange of the rail and an angular face of a lug formed on the tie-plate upon which the rail is supported, and the object of the invention is to provide simple, inexpensive means for holding the roller against vertical movement and thus preventing its escape from the angular space in which it performs its function.

15 20 The invention consists in certain novel features and details of construction by which the above object is attained, to be hereinafter described.

The accompanying drawings form a part 25 of this specification, and show approved forms of the invention.

Figure 1 is a plan view showing a portion of a rail held to a tie-plate by a preferred form of roller. Fig. 2 is a corresponding 30 vertical section, partly in elevation, the plane of section being indicated by the line 2—2 in Fig. 1. Fig. 3 is a plan view of the same roller on a greatly enlarged scale, Fig. 35 4 is a corresponding side view. Fig. 5 is a vertical section taken on the line 5—5 in the succeeding figure. Fig. 6 is a horizontal section through adjacent portions of the base-flange and roller, taken on the plane indicated in Fig. 5. Figs. 7 and 8 are side 40 elevations on a smaller scale, showing modified forms of the roller.

Similar letters of reference indicate like parts in all the figures.

A is the head of a rail and A¹ A² the base-flanges supported on the tie-plate B secured to the tie, not shown, by spikes D driven through holes b in the plate, with the spike-heads engaged with the base-flanges as usual. On the upper face of the tie-plate at 45 the outer end is a transverse rib or abutment B¹ engaged by the base-flange A¹ and serving to hold the rail against lateral movement outwardly, and on the opposite end is a transverse lug B² having its face adjacent 50 to the base-flange A² formed angularly rela-

tively to the edge of the flange as at b² b², the ends of the lug being nearer to the flange than the central portion and forming a flattened V-shape as shown in Fig. 1.

A roller E having vertical corrugations or teeth E' lies in the angular space thus provided and by its frictional engagement with the base-flange on one side and the angular face of the lug on the other, is partially rotated by the creeping movement of the rail upon the tie-plate until the roller is crowded into the gradually narrowing space to a point at which its grip upon the base-flange and lug is sufficient to hold the rail against further longitudinal movement. A single angular face b² will serve to hold the rail against creeping in one direction but the flattened V-shape is preferable for the reason that the roller is held against escape due to a reverse movement of the rail and also will hold the rail against movement in either direction.

The roller is preferably of such size as to fit closely in the widest portion of the angular space and engage both the lug and the base-flange, and the roller is applied by thus placing it while the base-flange is elevated and then forcing the rail downward into close contact with the tie-plate.

It is important that the roller be held against vertical movement which would permit its escape upwardly, and for economical reasons it is necessary that such holding means be simple and inexpensive.

In the preferred form shown in Figs. 1 to 6 inclusive, the teeth or corrugations extend nearly to the lower end of the roller, leaving a narrow rim or belt E² at the bottom, smoothly finished below the teeth E¹. This belt is of such width as to lie below the rounded angle A³ formed at the junction of the side-face A⁴ of the base-flange and the under face A⁵ thereof in all forms of standard rails, as shown in Fig. 5, and the roller is preferably of harder steel than the flange and lugs so that as the teeth E¹ of the roller are forced into the vertical face A⁴ of the flange, the smooth narrow belt E² projects beneath the angle of the flange, and by its engagement prevents vertical movement of the roller. The teeth and belt are also forced into the face of the lug in like manner but in less degree, and this engagement of the belt with the lug aids in resisting vertical movement.

To insure further against rising, the roller is preferably tapered very slightly to the form of a truncated cone, and the angular faces b^2 b^2 of the lug are similarly inclined or slightly undercut, as shown in Fig. 5. The face A^4 of the rail is vertical but is relatively narrow and the tapered roller engages satisfactorily therewith, the rounded angle A^3 facilitating such engagement by permitting the base of the conical roller to extend slightly thereunder.

The vertical inclination of the face of the abutment and the conicity of the roller are exaggerated in the drawings for the purpose 15 of illustration; an extremely slight taper will suffice and will serve successfully with a vertical face b^2 by reason of the greater depth to which the teeth E^1 will sink at the base of the roller.

20 A roller E^3 of true cylindrical form as shown in Fig. 7, having a narrow belt E^4 at its lower end will also serve successfully by reason of the engagement of such belt beneath the base-flange of the rail as before described, or the conical roller E^5 with the corrugations extending the entire length, as shown in Fig. 8, may be employed, depending upon the engagement of the tapered form with the face of the lug and rounded 30 angle of the base-flange to resist vertical movement.

I claim:—

1. In a device of the character set forth, a tie-plate adapted to support a rail, a lug 35 on said plate having an angular face adjacent to such rail, a flangeless roller in the angular space between said angular face and rail and engaging the base-flange of the rail, corrugations on said roller extending longitudinally thereof from the top nearly to the bottom, the remaining smooth portion at the bottom of said roller constructed to engage beneath the base-flange of the rail and hold said roller against vertical movement.
- 40 2. In a device of the character set forth, a tie-plate adapted to support a rail, a lug on said plate having an angular face adja-

cent to such rail, a roller in the angular space between said angular face and rail and engaging the base-flange of the rail, corrugations on said roller extending longitudinally thereof, said roller having the form of a truncated cone and constructed to engage at its base beneath the base-flange of the rail to hold said roller against vertical 55 movement.

3. In a device of the character set forth, a tie-plate adapted to support a rail, a lug on said plate having an angular face adjacent to such rail, a roller in the angular space between said angular face and rail and engaging the base-flange of the rail, such angular face being inclined upwardly toward such rail, corrugations on said roller extending longitudinally thereof, said roller 60 having the form of a truncated cone and constructed to match to and engage said upwardly inclined face of said lug and to engage beneath the base-flange of the rail to hold said roller against vertical movement. 70

4. In a device of the character set forth, a tie-plate adapted to support a rail, a lug on said plate having an angular face adjacent to such rail, such angular face inclined upwardly toward such rail, a roller in the angular space between said angular face and rail and engaging the base-flange of the rail, corrugations extending longitudinally of said roller from the top nearly to the bottom thereof, the remaining portion forming 80 a smooth belt at the bottom of said roller, the latter having the form of a truncated cone and constructed to be held against vertical movement by the engagement of said belt beneath the base-flange of a rail and 85 by the engagement with said upwardly inclined face of said lug.

In testimony that I claim the invention above set forth I affix my signature, in presence of two witnesses.

EDMUND B. POWERS.
